3,259,001 TOGGLE DEVICE

Friedrich W. Lampe, Detroit, Mich., assignor to Lapeer Manufacturing Company, Detroit, Mich., a corporation of Michigan

Filed Mar. 18, 1965, Ser. No. 440,891

5 Claims. (Cl. 81—351)

This invention relates to new and useful improvements in manually operated, toggle type, clamping or cutting devices, and more particularly to the provision of improved pivotal joints in devices of this type.

Certain types of tools, such as toggle tools of the type illustrated in the drawings, are provided with a plurality of pivotal joints between the handles and the jaws of the tool to enable the user to gain a mechanical advantage between the force applied to the handles and the resulting force applied to the work between the jaws. In using tools of this type for clamping pieces of work together, great forces are generated which are exerted against and must be transmitted by these pivotal joints. In conventional tools of which applicant is aware these forces are in the forms of sheer, torsional and tensile or compressive forces on the pivot pins of the pivotal joints.

Certain prior art tools of this type have been provided with four sets of pivot points, that is, a common pivot point between the jaws, a common pivot point between the handles, a common pivot point between one of the handles and one of the jaws, and a common pivot point between the other of the handles and the other of the jaws. The two resulting pivotal joints on each of these members have, in such tools, been formed on a single relatively flat flange portion thereon, so that the torsional and sheer forces acting through the joints on each member are in substantially the same planes. An example of such a tool is illustrated in my prior patent, No. 2,894,547, granted July 14, 1959. In this patent it is seen that each of the handles is formed of a generally elongated section constituting the handle proper and having a generally flat flange thereon through which are formed a pair of apertures, each receiving a pivot pin to define a pivotal joint. Each of the jaws are formed with a jaw proper and a generally flat flange having a pair of apertures therethrough adapted to receive pivot pins to define the two pivotal joints thereon. The flanges on the two handle extensions are positioned on opposite sides of the tool in partial facing relationship to one another, and the flanges on the two jaw portions are similarly positioned relative to one another. Each of the flanges acts as an interconnecting member between pivots on a given member. The important point to be noted here is that the two pivots on each member always act in substantially the same plane. It is with this aspect of the tool assembly that the present invention is primarily concerned.

A schematic diagram of the pivot pins of Patent 2,894,547 has been illustrated in FIG. 7 of the drawings and labeled "Prior Art." The diagram illustrates the inclination of the pivot pins as would result from the resolution of forces impressed thereon by the interconnecting members described above. As is seen from the figure, certain members have resulting forces impressed thereon which are perpendicular to the plane of the member and tend to displace the member in a direction axial to the pivot pins. One such member is the interconnecting member between the common pivot for the jaws and the right side common pivot for the jaw and handle. The force on this interconnecting member tends to force the member downwardly, thus separating the assembly. Similar forces may be found on the other members and these forces are offset by the heads or

2

backs of the rivets forming the pivot pins. In this situation, the frictional forces within the linkage are increased and the rivets must be made sufficiently strong to overcome the added force, resulting in an increased cost.

One solution for the force problem described above is to provide the tool with pivot points of the double shear type, as is particularly illustrated in my Patent No. 2,899,995, granted August 18, 1959. In this patent 10 it is to be seen that each of the pivot points is provided with a pair of interconnected elements, one of which has an end which is bifurcated axially of the pivot pin with the other member interfitting between the bifurcated ends. In this way the forces on the pin 15 are impressed strictly in shear, thereby solving the problem of an unbalance of axial forces on the pivot pin. However, in a construction of this type, it is necessary that the apertures through which the pin is passed, i.e., the bifurcated end, must be either drilled and milled or some other expensive and burdensome method must be used to form the apertures. The single portion which 20 is positioned between the bifurcated end may be punched but the problem still exists where there are any drilling operations. Also, the double shear method requires 25 additional material, creates a heavier and more cumbersome tool, and is more expensive to produce.

With the device of the present invention, the forces within the interconnecting members are so distributed as to substantially eliminate the axial forces created on 30 the heads of the rivets or ends of the fastener members which are used to retain the assembly in the assembled position. In this way, the frictional forces produced on the fastening means are substantially reduced and a greater portion of the force applied to the handle will 35 be transmitted to the jaw portions and anvil of the device. In an assembly constructed according to the present invention, the resultant forces are offset by an opposing member and by the shank or pin portion of the rivet in addition to the interaction of the other 40 members of the assembly.

Accordingly, it is one object of the present invention to provide an improved toggle type clamping or cutting device.

It is another object of the present invention to provide 45 a toggle type clamping or cutting device having an improved force distribution throughout the individual members of the device.

Another object of the present invention is to provide 50 a toggle type clamping or cutting device having an improved force transmitting characteristic.

Still another object of the present invention is to provide 55 a toggle type clamping or cutting device having practically no forces on the heads of the fastener members used to assemble the device.

Still another object of the present invention is to provide 60 an improved toggle type clamping or cutting device wherein the parts are manufactured by inexpensive methods, as by punching.

Still another object of the present invention is to provide 65 a toggle type clamping or cutting device which is lighter in weight and easier in use.

Further objects, features, and advantages of this invention will become apparent from a consideration of the following description, the appended claims and the 70 accompanying drawings in which:

FIGURE 1 is a plan view of a toggle type clamping device incorporating certain principles of the present invention;

FIG. 2 is a side view of the toggle type clamping 75 device of FIG. 1;

FIG. 3 is a sectional view of the device of FIG. 1 taken along lines 3—3 thereof;

FIG. 4 is a sectional view of the device of FIG. 1 taken along lines 4-4 thereof;

FIG. 5 is a sectional view of the device of FIG. 1 taken along lines 5-5 thereof;

FIG. 6 is a plan view of the toggle device of FIG. 1 illustrating the device in the open position;

FIG. 7 is a schematic diagram of the position of the pivot pins of the prior art device illustrating the action of the resultant forces on the pivot pins; and

FIG. 8 is a schematic diagram of the position of the pivot pins of the present invention illustrating the action of the resultant forces on the pivot pins.

Referring now to the drawings, there is illustrated a typical toggle type clamping pliers comprising a pair of jaws 12, 14 which are connected together by a common pivot connection 16. An anvil 18 is formed at the outer end of one of the jaws 12, 14 having an anvil surface 20 at an inner edge thereof and a spindle socket 22 is formed at an outer end of the other jaw which is adapted to threadably support a spindle 24. The spindle 24 may be rotatably adjusted within the spindle socket 22 to transversely adjust a spindle head 26 relative to the anvil surface 20. This adjustment is necessary to accommodate different workpiece sizes and, for a given workpiece size, to vary the force applied thereto. As is well known, when the gap between the head 26 and the anvil surface 20 is decreased to less than any given workpiece size, the clamping force is proportionally increased. The upper end of the spindle 24 is threadedly provided with a fastener or locknut member 28 which is adapted to bear against the outside surface of the jaw 12, thereby locking the spindle 24 in any selected position.

A pair of handles 32, 34 are connected together by a common pivot connection 36 and each handle 32, 34 is connected individually to a pair of jaws 12, 14, each by one of a pair of pivot connections indicated at 38 and 40, respectively. The free ends of the jaws 12, 14 are brought together by separation of their pivoted ends at the pivot connections 38 and 40, the jaws 12, 14 being fulcrumed on their common pivot connection 16. Conversely, the jaws 12, 14 are opened by relative movement of their pivoted ends toward each other by an opposite action at the pivot connections 38 and 40. The separation or bringing together of the pair of pivot connections 38, 40 occurs by movement of the common pivot connection 36 for the handles 32, 34 toward or away from connection 16 and between the pivot connections 38, 40. Thus, when the handles are squeezed together, their common pivot connection 36 is caused to move inwardly toward the throat of the pliers, thus separating the pivoted ends of the pair of jaws 12 and 14 and actuating their free ends together so that the spindle 24 moves closer to the anvil surface 20.

In order to clamp two objects or workpieces together, the workpieces are positioned between the anvil surface 20 and the spindle head 26 and a force is applied to the handles 32, 34 tending to force them together until the surface 20 and spindle head 26 engage opposite sides of the workpieces. Further movement of the spindle 24 toward the anvil surface 20 is resisted by the interposed workpieces so that it then becomes necessary to squeeze the handles 32 and 34 together with greater force which causes their common pivot connection to move to a position which is a position to be hereinafter referred to as the dead center position with respect to the pair of pivot connections 38 and 40. In the dead center position, the center of pivot connection 36 must be moved to a position which is intersected by a line drawn through the centers of pivot connections 38 and 40.

In final movement of the common pivot connection 36 into dead center condition, the pivoted ends of the pair of jaws 12, 14 separate but their free ends are held immobile by the pair of workpieces that are to be clamped. In this situation, the force is such that the body of the jaws 12 and 14 are flexed under load and a certain

amount of force, depending on the setting of the spindle 24, is stored in the jaws when they are thus clamped under load. In this position, since the common pivot connection 36 is in dead center condition with relation to the pair of pivot connections 38 and 40, no amount of force applied to the pair of jaws 12 and 14, short of breakage of parts, will cause them to be separated.

The jaws 12 and 14 are provided with a pair of flat rib members 44, 46, respectively, which serve to strengthen the jaws 12, 14, thus precluding their breakage and decreasing the amount of flexing for the amount of force stored therein. The handles, however, may be separated to actuate the pair of jaws 12, 14 out of the closed, locked position without any prying means or members. However, an unlocking device, such as that shown in my patent No. 2,894,547 may be incorporated into the unit to facilitate the opening of the toggle device.

The outward motion of the common pivot 36 is limited by the inner corners of the handles which abut each other at point 36a. The travel of the pivot point 36 beyond the dead center position is stopped by a pair of stop members 50, 52 formed on jaws 12, 14 and no amount of force applied to the handles will overdrive the pivot point 36. A pair of web members 54, 56 are integrally formed with the handle 32, 34 for structural purposes and also providing mounting members which are adapted to support a handle or opening mechanism such as that illustrated in my patent No. 2,894,547. The assembly is further strengthened by providing built-up portions 58, 60 which provide additional structural rigidity to the stress points of the structure or part of that tool.

Referring now to the details of the common pivot points, as illustrated in FIGS. 3-5, and the orientation diagram of the pivot pins, as illustrated in FIG. 8, it is seen that the interconnecting elements described above are particularly arranged to offset the axial forces created therein by means of the particular offset relation of the pairs of flat portions. The particular details of the common pivot points will be described in a round robin fashion starting with pivot point 40 and proceeding through pivot points 36, 38, to pivot point 16, and back to pivot point 40. In this way, the particular relationships between the forces acting on the pivot pins will be particularly seen.

Structurally, the handle 34 is formed with the end member 66 having a first flat portion 68 and a second flat portion 70 offset therefrom. The portions 68 and 70 are formed with a pair of apertures 72, 74, respectively, which are adapted to receive a pair of pivot pins 76, 78. The pivot pins 76, 78 may be of the rivet type having a head, a shank, and a backing portion. The other handle 32 is similarly formed with an end portion 80 having a third flat portion 82 and a fourth flat portion 84, in a manner similar to that described above.

The two portions 82 and 84 have a pair of apertures 86 and 88 formed therein which are adapted to receive the pivot pin 78 which is common with the second portion 70 and a similar pin 90 which passes through the aperture formed in fourth portion 84. The jaw member 12 is similarly formed with fifth and sixth offset flat end portions 94, 96 having a pair of apertures formed therein, 98 and 100, respectively. The aperture 98 is aligned with the aperture 88 and receives pin 90 and the aperture 100 is aligned with an aperture 102 in a seventh offset member 104 of the other jaw 14, the two apertures 100, 102 being adapted to receive a pin 106. The jaw member 14 is formed with an eighth offset portion 110 having an aperture therein 112 which is adapted to receive the pin 76 described above.

In FIG. 7, the forces on the prior art common pivot points are illustrated. By way of analogy, the common pivot points have been indicated by the primed numerals which correspond to the reference numerals of the common pivots described above. Thus, pivot 106' corre-

sponds to the common pivot 106 between the pair of jaws, pivot 78' the common pivot between the handles and pivots 76' and 90' corresponds to the common pivot between each handle and its respective jaw. The dashed lines indicate a connection between common pivots which has been made at the bottom of the pins and the dot-dashed lines the connection between common pivots made at the top of the pins. This interconnection of common pivots is specifically illustrated in my Patent Number 2,894,547.

As the actuating force is applied to the handles of the prior art device, a force is seen to be applied along a line to the right at the top of pivot 76' and to the left at the top of pivot 78' by the interconnecting member between pivots 76' and 78'. A force generally to the left is applied at the bottom of pivot 76' and to the right at the bottom of pivot 106' by the interconnecting member between pivots 76' and 106'. Similarly, a force generally to the left is applied at the top of pivot 106' and to the right at the top of pivot 90' by the interconnecting members between pivots 106' and 90'. Lastly, the bottom of pivot 90' is urged to the left by a force to the left and the bottom of pivot 78' is urged to the right by a force directed to the right, both latter forces being supplied by the interconnection between pivots 90' and 78'.

With the above described system of forces, each of the interconnecting members is subjected to a force axially of the pivot axis which tends to force the interconnecting members apart. This force is opposed by friction on the pivot pins and the rivet heads, thus increasing the frictional forces within the system. Also, the various rivet parts must be fabricated of a more sturdy material, thereby increasing the cost of the unit. The forces on the pivot pins of a unit embodying the principles of the present invention is illustrated in FIG. 8, where parts corresponding to those described above have been given like reference numerals. Also, the representation of interconnecting member connected to the bottom of pivot pins have been illustrated by dotted lines while those connected to the top of the pivot pins have been indicated in dot-dashed lines.

As is seen from FIG. 8, all of the forces on the bottoms of the pivot pins are in the same direction, to the left, while all the forces on the tops of the pivot pins are to the right. In analyzing the forces on the pins, it is seen that the members 96, 104 acting on pin 106 urge the bottom of the pin to the left and the top to the right, respectively. This is due to the spreading of the jaws 12, 14 by spindle 24 and the action of the linkage through line 3—3 of FIG. 1. Similarly, members 84, 94 act on pin 90 tending to tilt the pin in the same direction, members 82, 70 act on pin 78 and members 68, 110 act on pin 76, as illustrated, by the general plan view of the pivot pins.

The reaction forces on the various members of the assembly caused by the forces on the pins are offset through the interaction of the pairs of flat portions which are in face abutting relation and interconnected by a pivot pin. Thus, a force tending to axially urge a flat portion outwardly is offset by the other of the pair of flat portions interacting with the mating portion of its pivot pin. For example, in the assembly illustrated in FIG. 3, if a force were created on member 70 tending to urge it outwardly or to the left, a reaction force would be set up in member 68 against member 110, thereby offsetting the outwardly acting force. These reaction forces are impressed on the members in a closed chain and the net result is a zero force tending to separate the various flat portions.

With the arrangement described above, the toggle device is so constructed as to offset the internal forces of the member within its own structure. Thus the axial loading of the pivot pins is reduced and the material used to fabricate the heads of the pins may be reduced because the function of the heads is mainly to retain the pins. Also, with the construction described above, the forces on the pins are mainly in shear, thereby reducing the fric-

tional forces between the moving parts. In this way the device becomes easier to use as a greater proportion of the actuating force is transmitted to the jaws of the device. While the device has been described in conjunction with a device having four common pivots, it is to be understood that the invention may be practiced on a device having a greater or lesser number of pivot points.

While it will be apparent that the embodiment of the invention herein disclosed is well calculated to fulfill the objects of the invention, it will be appreciated that the invention is susceptible to modification, variation and change without departing from the proper scope or fair meaning of the subjoined claims.

What is claimed is:

1. A toggle device comprising:
first and second jaw members pivotally mounted for travel toward and away from each other,
first and second handle members pivotally mounted for travel toward and away from each other in response to forces applied thereto, and
means connecting said handle members and said jaw members for transmitting to said jaw members forces applied to said handle members and substantially reducing outward forces on said handle and jaw members tending to separate said members including,
interconnecting means formed on each of said jaw and handle members having a first flat portion formed in a first plane and a second flat portion formed in a second plane spaced from and parallel to said first plane,
means formed in each of said flat portions for receiving a pivot means,
said first flat portion on each of said members lying in overlapping relation to said second flat portion of the member connected thereto with said pivot receiving means in axial aligned relation, and
pivot means received in each of said axial aligned pairs of pivot receiving means for maintaining said toggle device in assembled relation.

2. A toggle device comprising:
first and second jaw members pivotally mounted for travel toward and away from each other,
first and second handle members pivotally mounted for travel toward and away from each other in response to forces applied thereto, and
means connecting said handle members and said jaw members for transmitting to said jaw members forces applied to said handle members and substantially reducing outward forces on said handle and jaw members tending to separate said members including,
interconnecting means formed on each of said jaw and handle members having a first flat portion formed in a first plane and a second flat portion formed in a second plane spaced from and parallel to said first plane,
said first flat portion of said first handle member lying in overlapping relation to said second flat portion of said first jaw,
said first flat portion of said first jaw lying in overlapping relation to said second flat portion of said second jaw,
said first flat portion of said second jaw lying in overlapping relation to the second flat portion of said second handle member,
said first flat portion of said second handle member lying in overlapping relation to said second flat portion of said first handle member,
pivot means interconnecting each of said overlapping pairs of flat portions for maintaining said toggle device in assembled relation.

3. A toggle device comprising:
first and second jaw members pivotally mounted for travel toward and away from each other,
first and second handle members pivotally mounted for

travel toward and away from each other in response to forces applied thereto, and means connecting said handle members and said jaw members for transmitting to said jaw members forces applied to said handle members and substantially reducing outward forces on said handle and jaw members tending to separate said members including, interconnecting means formed on each of said jaw and handle members having a first flat portion formed in a first plane and a second flat portion formed in a second plane spaced from and parallel to said first plane, means formed on each of said flat portions for receiving a pivot means, said first flat portion of said first handle member lying in overlapping relation to said second flat portion of said first jaw with said pivot receiving means in axial aligned relation, said first flat portion of said first jaw lying in overlapping relation to said second flat portion of said second jaw with said pivot receiving means in axial aligned relation, said first flat portion of said second jaw lying in overlapping relation to said second flat portion of said second handle member with said pivot receiving means in axial aligned relation, said first flat portion of said second handle member lying in overlapping relation to said second flat portion of said first handle member with said pivot receiving means in axial aligned relation, and pivot means received in each said axial aligned pairs of pivot receiving means for maintaining said toggle device in assembled relation.

4. A toggle device comprising:

first and second jaw members pivotally mounted for travel toward and away from each other, first and second handle members pivotally mounted for travel toward and away from each other in response to forces applied thereto, and means connecting said handle members and said jaw members for transmitting to said jaw members forces applied to said handle members and substantially reducing outward forces on said handle and jaw members tending to separate said members including, interconnecting means formed at one end of each of said jaw and handle members having a first flat portion formed in a first plane and a second flat portion formed in a second plane spaced from and parallel to said first plane, pin receiving apertures formed on each of said flat portions for receiving means, said first flat portion of said first handle member lying in overlapping relation to said second flat portion of said first jaw with said pin receiving apertures in axial aligned relation, said first flat portion of said first jaw lying in overlapping relation to said second flat portion of said second jaw with said pin receiving apertures in axial aligned relation, and said first flat portion of said second jaw lying in over-

lapping relation to said second flat portion of said second handle member with said pin receiving apertures in axial aligned relation, said first flat portion of said second handle member lying in overlapping relation to said second flat portion of said first handle member with said pin receiving apertures in axial aligned relation, and pin means received in each said axial aligned pairs of pin apertures for maintaining said toggle device in assembled relation.

5. A toggle device comprising:

first and second jaw members pivotally mounted for travel toward and away from each other, first and second handle members pivotally mounted for travel toward and away from each other in response to forces applied thereto, and a linkage assembly connecting said handle members and said jaw members for transmitting to said jaw members forces applied to said handle members and substantially reducing outward forces on said handle and jaw members including, an interconnecting member formed at one end of each of said jaw and handle members having a first flat portion formed in a first plane, a second flat portion formed in a second plane spaced from and parallel to said first plane and a portion connecting said first and second flat portions, pin receiving apertures formed in each of said flat portions for receiving a pivot pin, said first flat portion of said first handle member lying in overlapping relation to said second flat portion of said first jaw with said pin receiving apertures in axial aligned relation, said first flat portion of said first jaw lying in overlapping relation to said second flat portion of said second jaw with said pin receiving apertures in axial aligned relation, said first flat portion of said second jaw lying in overlapping relation to said second flat portion of said second handle member with said pin receiving apertures in axial aligned relation, said first flat portion of said second handle member lying in overlapping relation to said second flat portion of said first handle member with said pin receiving apertures in axial aligned relation, and a pivot pin received in each said axial aligned pairs of pin apertures for maintaining said toggle device in assembled relation, said second flat portion of said first handle member and said first flat portion of said second handle member forming with said pivot pin an overcenter locking connection for locking said jaw members in a closed position.
